UNITED STATES PATENT OFFICE.

GEORGE A. FITCH, OF OAKLAND, NEW YORK.

SPEAKING-TELEPHONE.

SPECIFICATION forming part of Letters Patent No. 269,657, dated December 26, 1882.

Application filed March 4, 1882. (No model.)

To all whom it may concern:

Be it known that I, GEORGE A. FITCH, of Oakland, in the county of Livingston and State of New York, have invented a new and useful Improvement in Speaking-Telephones, of which the following is a full, clear, and exact description, reference being had to the annexed drawings, forming part of this specification.

My invention relates to an improvement in receiving-instruments for the electrical speaking-telephone; and the invention consists of an apparatus in which a strip of suitable material is connected to a diaphragm and passed between two rotating rollers, one of which rollers is supported in the armature of an electro-magnet. The armature is provided with an adjusting-spring to prevent it from responding to induced or minor currents. When an electric current is passed through the rotating rollers and the strip the friction between the said parts will be increased or diminished in proportion to the varying intensity of the current, and a corresponding vibration of the diaphragm will be produced.

In the accompanying drawings, Figure 1 is a vertical section of an instrument embodying my invention. Fig. 2 is a horizontal section of the same. Fig. 3 is an edge view of the rollers and armature, the latter being in section. Fig. 4 is a vertical section of an instrument, showing the rollers arranged in the reverse order of that shown in Fig. 1; and Fig. 5 shows a modified form of roller and strip.

In loud-speaking telephones it has been attempted heretofore to connect a receiving-diaphragm with a transmitting apparatus by means of a strip of metal which is connected to the diaphragm and arranged under a given pressure between two chemically-prepared rotating rollers, whereby when a current is passed through the rollers and the strip the passage of the current shall act as a lubricant between the strip and rollers and cause the pressure on the strip to be released at intervals, thus causing the variations of the current to be recorded in vibrations of the diaphragm. In my invention, on the contrary, I dispense with the chemical element of the apparatus and employ a roller which is adapted to be rotated by hand-gear, clock-work, or by electro-

magnetism, and a pressure-roller which is placed in connection with an electro-magnet by means of an adjustable armature in such manner that the latter roller shall be made to bear with a variable pressure on a suitable strip connected to the diaphragm.

The arrangement of these parts will be clearly understood by reference to the drawings, in which A represents the mouth-piece, B the diaphragm, and C a box in which are supported by the frame D the magnets E E, the revolving armature F, and the rotating roller G; the said magnets and armature constituting the electro-motor. A second roller, H, is adapted to rotate on a spindle attached to the armature I, while the said armature I is connected to an arm, J, which forms a flexible joint with the post K, and the line electro-magnet L M is so placed that the current will act upon the armature I and cause the roller H to bear with a corresponding pressure on the strip N, which is connected to the diaphragm and passed between the peripheral surfaces of the rollers. As shown in Fig. 3, one of the rollers is provided with guiding-flanges to prevent the strip from becoming accidentally displaced. In Fig. 1 a permanent magnet, O, is shown connected to the line electro-magnet L M.

The armature I may be adjusted by means of a supporting-spring, P, and a screw, Q, for varying the tension of the spring, and the roller H, which is supported by said armature, may be arranged either as shown in Fig. 1, where it is represented above the roller G, or as shown in Fig. 4, where it under said roller. In the latter case the adjusting-spring P is adapted to exert a given pressure of the roller H against the strip, and the vibrations of the diaphragm are produced by the electro-motive force exerted on the armature, thereby overcoming the tension of spring P and allowing the strip to be released from pressure.

Instead of a flat strip, as shown in Fig. 3, I may sometimes use a triangular strip, as shown in Fig. 5, and construct one of the rollers with a V-groove to receive one of the edges of the triangular strip.

In Figs. 2 and 4 I have shown a perforated diaphragm arranged inside of and parallel with the diaphragm B to form an air-chamber; but

I do not attach any special importance to this feature, and it may be omitted without affecting the merits of my invention.

Having thus described my invention, what I claim as new, and desire to secure by Letters Patent, is—

1. In a telephone, the combination, with a diaphragm, of a strip of suitable material connected thereto and two rotating rollers between which the strip is placed, an electro-magnet, and an adjustable armature supporting one of the rollers, substantially as shown and described.

2. In a telephone, the combination of a roller supported in a stationary frame and means for rotating said roller, a second roller supported in an armature, an adjustable spring supporting the armature, an electro-magnet, and a strip of suitable material connected to a diaphragm and arranged between the rollers, substantially as shown and described.

3. In a telephone, the combination, with the rollers, the armature supporting one of the rollers, the electro-magnets, and the strip arranged between the rollers, of a spring supporting the armature and adapted to produce a greater or less tension thereon, whereby the armature shall not respond to induced currents, as specified. 25

4. In a telephone, the combination, with a cylindrical roller and means for supporting the same, of a grooved or flanged roller and a strip of material of corresponding form arranged between the rollers and connected to a diaphragm, substantially as shown and described. 35

GEO. A. FITCH.
